CABINET FOR ELECTRONIC EQUIPMENT

Charles E. Bozarth, Phoenix, Ariz., assignor to General
Electric Company, a corporation of New York

Original design application Feb. 26, 1964, Ser. No. 78,788.
Divided and this application Dec. 29, 1964, Ser. No.
83,200

Term of patent 14 years

(Cl. D26—5)

FIG. 1

FIG. 2

FIG. 3

FIG. 4

FIG. 1 is a top plan view of a cabinet for electronic equipment embodying my new design;

FIG. 2 is a perspective view thereof taken along the line 2—2 in FIG. 1;

FIG. 3 is a perspective view thereof taken along the line 3—3 in FIG. 1; and

FIG. 4 is a perspective view thereof taken along the line 4—4 in FIG. 1.

This application is a division of my earlier filed pending application, Serial No. D. 78,788, filed February 26, 1964.

I claim:

The ornamental design for a cabinet for electronic equipment, as shown and described.
